UNITED STATES PATENT OFFICE.

EDWIN WATKINS, OF BADAXE, MICHIGAN.

SNAP-HOOK.

SPECIFICATION forming part of Letters Patent No. 629,224, dated July 18, 1899.

Application filed April 26, 1898. Serial No. 678,897. (No model.)

To all whom it may concern:

Be it known that I, EDWIN WATKINS, a citizen of the United States, and a resident of Badaxe, in the county of Huron and State of Michigan, have invented certain new and useful Improvements in Snap-Hooks; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a side view of my improved snap-hook. Fig. 2 is an edge view of same, and Fig. 3 is a side view with the jaws spread.

This invention is designed to provide a snap-hook of novel and useful character; and it consists in a snap-hook formed from wire and of the peculiar construction hereinafter described, and pointed out in the appended claim.

In the manufacture of my improved snap-hook I take a piece of wire and form the central portion thereof into two coils. These coils are shown at A in the accompanying drawings and may be made of oblong or oval form, if desired, in order to form a broader loop for the reception of a strap or rope. Leaving the coils the two branches of the wire are each laterally deflected to meet and cross the other branch upon the opposite side of the snap-hook from the coil from which it proceeds and adjacent to the coils. The branches are then each given a twist at about right angles and diverge from each other to form a compression-loop B, each branch of the loop extending out upon the same side of the snap-hook as the coil from which it proceeds. The two branches of the wire are then again brought together and are again intercrossed, but in the opposite direction to the first intercrossing. Each branch of the wire is formed at this point with a lateral offset b, said offsets interlocking to limit the closing movement of said branches upon each other in a direction at approximately right angles to the plane of the loop B. From this offset the two branches run substantially parallel with each other for a short distance and terminate in semicircular open hook or jaw

portions C, which lie in planes at right angles to the plane of the coils A and in the plane of the loop B and which lap or spring 55 past each other, as shown.

It will be readily seen that when these hooks are engaged with a ring or the like into which they are snapped they cannot become disengaged without the aid of the hand, but that 60 by pressing together the two branches of the wire at the bends b' of the loop B the two hooks will readily separate to permit their engagement and disengagement. Therefore the hook may be readily engaged or disengaged 65 even though one's fingers are benumbed with cold and without removing the glove or mitten from the hand. It can also be disengaged without taking up the slack in the strap.

It will be noticed that when the loop B is 70 compressed the branches of the wire leaving the coils will take a pivotal bearing upon opposite sides of the upper connecting-arm of the coils and exert a leverage to spread said coils at the bottom, (see Fig. 3)—that is to 75 say, for a given compression of the loop a greater torsion of the coils is effected than when the center of pivotal movement is at the bottom of the coils, as is the case with any other mode of forming the coils and loop. A 80 stronger spring action of the coils is the result.

Having thus described my invention, what I claim as new, and desire to secure by Letters Patent, is—

The herein-described snap-hook, formed from a single piece of wire bent at its central portion to form two coils, the two branches of the wire leaving the coils being each laterally deflected to cross the other branch, upon the 90 opposite side of the snap-hook from the coil from which it proceeds, then given a twist at about right angles and diverged to form a compression-loop, the arms of said loop extending out each upon the same side of the 95 snap-hook as the coil from which it proceeds, and terminating at their extremities in overlapping hooks, substantially as specified.

In testimony whereof I affix my signature in presence of two witnesses.

EDWIN WATKINS.
